DESIGN FOR A COMBINED PERFUME CONTAINER AND STAND THEREFOR

Florence N. Lewis, New York, N. Y.

Application November 4, 1938, Serial No. 80,872

Term of patent 7 years

To all whom it may concern:

Be it known that I, Florence N. Lewis, a citizen of the United States, residing at New York, in the county of New York and State of New York, have invented a new, original, and ornamental Design for a Combined Perfume Container and Stand Therefor, of which the following is a specification, reference being had to the accompanying drawing, forming part thereof.

In the drawing

Fig. 1 is a side view of a combined perfume container and stand therefor, showing my new design;

Fig. 2 is a front view thereof;

Fig. 3 is a section through line 3—3 of Fig. 2.

I claim:

The ornamental design for a combined perfume container and stand therefor, as shown.

FLORENCE N. LEWIS.
